[57] CLAIM

The ornamental design for a belt mounted cigarette case or the like, substantially as shown and described.

DESCRIPTION

FIG. 1 is a top plan view of a belt mounted cigarette case or the like showing my new design;

FIG. 2 is a front elevational view thereof;

FIG. 3 is a side elevational view, the opposite side is a mirror image thereof;

FIG. 4 is a rear elevational view thereof; and

FIG. 5 is a bottom plan view thereof.

The broken lines on the case indicate stitching.

FIG. 1

FIG. 2

FIG. 3

FIG. 4

FIG. 5
